UNITED STATES PATENT OFFICE.

EDMOND FLORIMOND LEVAIRE, OF PARIS, FRANCE.

FASTENING MEANS FOR VIGNOLE RAILS.

1,396,271.

Specification of Letters Patent.

Patented Nov. 8, 1921.

Application filed December 9, 1919. Serial No. 343,647.

(GRANTED UNDER THE PROVISIONS OF THE ACT OF MARCH 3, 1921, 41 STAT. L., 1313.)

To all whom it may concern:

Be it known that I, EDMOND FLORIMOND LEVAIRE, citizen of the Republic of France, residing at 4 Rue Jouffroy, Paris, in the Republic of France, have invented new and useful Improvements in Fastening Means for Vignole Rails, (for which I have filed applications in France, Mar. 21, 1918, Patent No. 489,477, and Apr. 20, 1918, Patent No. 20,789, add.,) of which the following is a specification.

This invention relates to means for fastening Vignole or flange rails, comprising essentially the combination of a metal sole-plate having two hooks or claws and secured to the sleeper or formed integrally therewith, with two keys adapted to be forcibly driven between each claw and the rail flange, said keys being driven both in the same direction parallel to the rail, and having no contact with the web of the latter, even occasionally.

In the annexed drawings:

Figure 1 is a vertical section showing by way of example one embodiment of the securing device for Vignole rails in accordance with the invention.

Fig. 2 is a plan view of the same.

Fig. 3 is a perspective view of a metal sole-plate provided with two hooks or claws.

Fig. 4 is a section of the central part of the sole-plate or of the sleeper when the latter is itself provided with claws, said central part being shown with the shape it assumes, when said element is delivered by the finishing rolling mill.

Fig. 5 is an end view of one of the keys in active position.

Fig. 6 is a corresponding cross section of the same key about midway of the length thereof.

Figs. 7, 8 and 9 are an inverted plan view, a plan view and a side view, respectively, of a key.

Fig. 10 is a cross section showing a modification of the key, said section being made about midway of its length.

Fig. 11 is a cross section of another modification, said section being taken about midway of its length.

As shown in the drawings, the flange rail *b* is secured to the sleepers by means of a device comprising a metal sole-plate *c* provided with two claws *c*¹ *c*² and two keys *a* and *a*¹ which are forcibly driven into the space between each claw and the corresponding

flange of the rail, respectively. The claws may be formed integral with the sleeper, the sole-plate being omitted. The two keys are inserted in the same direction parallel to the rail, the web of the rail being never used as a supporting member for the keys, even occasionally.

The general shape of the key is that of a tapered prism whose edges are preferably replaced by fillets. Said prism contacts with the rail by two faces along the lateral edge of the rail flange. While the contact of a coach-screw with a rail takes place along one line underneath its head and along another line, along its shank, the contact of the key with the rail takes place by two rectangular faces having approximately these two lines for their height, respectively. In no other place is the rail used as a supporting member for the key. The key is inserted between the rail flange and the claw, its shape conforming with that of the inner walls of said claw, which tapers longitudinally.

Figs. 10 and 11 show that the contact between the key and the claw may be dispensed with in the fillet part 6—7 of the claw. At this place, the fillet on the key may be flattened or it may have a radius somewhat greater than that of the corresponding fillet provided on the claw, as shown in Fig. 10, or it may be concave instead of being convex, as shown in Fig. 11, so that there is no clamping pressure between fillets or curved parts, the pressure received by the claw from the key being exerted on the inner faces of the claw *i. e.* the upper inner face and the side inner face of the same.

The inner side faces of the two opposite claws are spaced apart by a sufficient distance so that different track gages may be obtained by using keys having a suitable thickness. The distance between the claws at the top is equal to the width of the rail flange plus a sufficient clearance to allow an easy insertion of the rail flange between the claws in a vertical direction.

The space between the two claws on the sole-plate forms a chamber for the rail and the two keys. Its general shape is that of a tapered prism as shown at *o*—*n*—*m*—*r*—*q*—*p*—*v*—*x*—*y*—*s*—*t*—*u* in Fig. 3, the same being formed by a rectangular prism having for its base an isosceles trapezium *m*—*n*—*o*—*p*—*q*—*r*— and being beveled along the three

planes $m-n-s-t$, $q-r-y-x$, $n-q-x-t$ inclined by the same angle to the three planes $m-n-n'-m'$, $q-r-r'-q'$, $n-q-q'-n'$, respectively. The lines $m-s$, $r-y$, 5 $n-t$ and $q-x$ are thus inclined by the same angle to the lines $m-m'$, $r-r'$, $n-n'$, $q-q'$. The slope is about 25 millimeters per meter. It may be increased or reduced as desired.

The face $o-n-m-r-q-p$ is the larger 10 opening of the rail chamber and the face $u-t-s-y-x-v$ is the smaller opening of the same, the flange of the rail resting upon the face $m-r-y-s$.

The edges $m-s$, $r-y$, $n-t$ and $q-x$ are 15 beveled or filleted and form a portion of a cylindrical or other surface *i. e.* the sharp edges at m , n , s , t , r , q , y , and x are replaced by fillets.

The sloping planes $n-o-u-t$, $p-q-x-v$ 20 are for the purpose of fastening the rail in a vertical direction by means of the clamping pressure exerted upon said rail in a vertical direction when the keys are driven inside the claws. The sloping planes $m-n-t-s$, $r-q-x-y$ 25 are for the purpose of fastening the rail laterally owing to the clamping pressure developed in a lateral direction upon the rail when the keys are inserted.

It will be seen in Figs. 10 and 11 that any 30 contact between the sole-plate and the key may be done away with in the filleted part 6-7. This may be effected also in any other curved portion.

When each key has been forcibly driven to 35 its working position, it is locked in the longitudinal direction so as to prevent any possible loosening. This is effected by means of a wire f or f' having a square cross section which is inserted into a longitudinal 40 groove g in the key and is held at one end by having its bent extremity engaging into a hole h provided in the key at the side of the larger base thereof, a portion of said wire being folded at its other end against 45 the lateral face of the claw.

The construction above described insures a rigid assembling of the parts and a strong clamping action which opposes any displacement of the rail either in the longitudinal 50 direction, transverse direction or vertically from below upward.

As will be readily understood, the metal sole-plate c may be separate from the sleeper or formed integrally with the latter. Also, 55 the hooks or claws c' and c'' may be provided on a portion only of the width of the sole-plate as shown in Fig. 2 or they may extend along the entire width thereof.

The device above described for locking 60 the keys in the longitudinal direction may be replaced by any other suitable means or even entirely dispensed with. The wire may of course be replaced by a flat metal band or by a band having any other suitable profile.

65 Figs. 5 to 9 show in detail the shape of

a key, which is on the whole that of a tapered prism. From point 1 to point 2 (Fig. 6) the inner face of the key has a shape corresponding to the upper face of the rail flange. Then, it conforms with the most 70 part 3-4 of the vertical lateral face of the flange. The under face of the key is formed by a plane inclined surface 4-5, the point 5 being at the lower inner angle of the claw. The sharp edge 5 may be replaced 75 by a fillet 5'.

It will be noted that there is no play between the part of the side face of the rail flange which is at right angles to the bottom of the rail chamber and the portion 3-4 80 of the inner surface of the key.

The lateral and upper portions 5-6 and 6-7-8-9 respectively of the surface of the key conform to the shape of the inner surface of the claw. Contact may however be 85 omitted in the curved portion 6-7. On the inner side opposite the rail, the surface of the key comprises a rounded part 9-10 merging tangentially into a flat portion 10-1.

The longitudinal surface 9-10-1 may be 90 parallel to the rail or inclined thereto in the same direction as the longitudinal face in contact with the inner face of the claw or in the reverse direction. The contour 95 line 1-10-9 of the cross section of the key may form a right angle having its apex near point 10, or an acute angle or still an obtuse angle, the apex of this angle being rounded or filleted. The part of the key outside the 100 claw, adjacent point 9, may also extend to a higher level than the line 9-8-7.

The upper straight portion 7-8-9 of the 105 cross-sectional area of the key may be parallel to the bottom of the rail chamber or slope slightly toward the center of the under face of the rail flange. The line 9-8-7-6 may also be replaced by a straight line starting from 9 or thereabout and directed toward point 6 or toward a point underneath 6 110 with an inclination of about 21 degrees to the bottom of the rail chamber, said straight portion being connected to the portions 5-6 and 9-10 by fillets. These modifications may be adopted for the purpose of meeting 115 any desired conditions with regard to the clamping action or the manufacture of the parts.

The fillet connecting the face 1-2 of the key to the vertical face 3-4 of said key 120 has a smaller radius than the corresponding fillet on the rail flange so that the two fillets are not in contact.

The key whose length is about 180 millimeters for heavy rails has a taper from the 125 big end to the small end, at least in the part 5-6-7-8-9, of about 25 millimeters to the meter. Said inclination which is also that of the walls of the claw c' may be increased or diminished as desired. 130

Each end face of the key is plane and beveled or filleted along its edge. It may also be convex.

As a result of the combination of the portion 7-8-9 which is either parallel to the bottom or bearing face of the rail chamber, slightly inclined toward the center of the rail flange or inclined in the opposite direction by about 21 degrees with respect to the 10 said bearing face of the rail chamber, with the inclined bottom face 1-2, the key can never slip out of the rail chamber in a transverse direction through the space 2-9. As a matter of fact, the inner shape of the claws 15 must conform along the line 5-6-7-8-9 to that of the key as above described, except possibly from 6 to 7.

Fig. 10 shows a modification in which the lower outer edge 5 is filleted at 5'.

Fig. 11 shows a modification in which contact between the key and the claw is avoided in the part 6-7 by providing the key with a concave longitudinal recess or rabbet.

Having now described my invention, what 25 I claim as new and desire to secure by Letters Patent is:

1. A fastening device for Vignole rails comprising the combination of a metal supporting member, two lateral opposite claws integral with the said supporting member having a substantially horizontal projecting or beak portion, the inner under side of each beak portion being situated in a plane at right angle with the web part of the rail, 30 but slightly inclined longitudinally toward the rail flange and a body portion and two tapering keys adapted to be forcibly driven between one claw on the said supporting member and one edge of the rail flange, respectively, both keys having their upper faces in slightly inclined planes, at right angle with the web part of the rail, the under faces being inclined to the bottom of the rail chamber being preferably driven in 35 the same direction and having no contact with the web part of the rail.

2. A fastening device for Vignole rails comprising the combination of a metal supporting member, two lateral opposite claws integral with the said supporting member, and having a substantially horizontal projecting or beak portion, the inner under side 40 of each beak portion being situated in a plane at right angle with the web part of the rail, but slightly inclined longitudinally toward the rail flange and a body portion and two tapering keys adapted to be forcibly driven between one claw on the said supporting member and one edge of the rail flange, respectively, both keys having their upper faces in slightly inclined planes, at 45 right angle with the web part of the rail, the under faces being inclined to the bottom of the rail chamber being driven in the same direction and having no contact with the web part of the rail, each key being 50

web part of the rail, each key being wedged between the upper face and the side face of the rail flange on the one hand and the inner side wall of the body portion of the claw and the bottom face of the beak portion 55 of the claw, on the other hand.

3. A fastening device for Vignole rails comprising the combination of a metal supporting member, two lateral opposite claws integral with the said supporting member 60 and having a substantially horizontal projecting or beak portion, the inner under side of each beak portion being situated in a plane at right angle with the web part of the rail, but slightly inclined longitudinally 65 toward the rail flange and a body portion, and two tapering keys adapted to be forcibly driven between one claw on the said supporting member and one edge of the rail flange, respectively, both keys having their upper faces in slightly inclined planes, at 70 right angle with the web part of the rail, the under faces being inclined to the bottom of the rail chamber being driven in the same direction and having no contact with the web part of the rail, each key being wedged between the upper face and the side face of the rail flange on the one hand and the inner side wall of the body portion of the claw and the bottom face of the beak portion 75 of the claw, on the other hand.

4. A fastening device for Vignole rails comprising the combination of a metal supporting member, two lateral opposite claws integral with the said supporting member, and having a substantially horizontal projecting or beak portion, the inner under side 80 of each beak portion being situated in a plane at right angle with the web part of the rail, but slightly inclined longitudinally 85 toward the rail flange and a body portion, and two tapering keys adapted to be forcibly driven between one claw on the said supporting member and one edge of the rail flange, respectively, both keys having their upper faces in slightly inclined planes, at 90 right angle with the web part of the rail, the under faces being inclined to the bottom of the rail chamber being driven in the same direction and having no contact with the web part of the rail, each key being 95

wedged between the upper face and the side 100

face of the rail flange, on the one hand and the inner side wall of the body portion of the claw and the bottom face of the beak portion of the claw on the other hand, the supporting member having fillets at its inner corners and the keys having corresponding fillets of a smaller radius, whereby no contact exists at the corners between the supporting member and the keys.

10 5. A fastening device for Vignole rails comprising the combination of a metal supporting member, two lateral opposite claws integral with the said supporting members and having a substantially horizontal projecting or beak portion, the inner under side of each beak portion being situated in a plane at right angle with the web part of the rail, but slightly inclined longitudinally toward the rail flange and a body portion 15 and two tapering keys adapted to be forcibly driven between one claw on the said supporting member and one edge of the rail flange, respectively, both keys having their upper faces in slightly inclined planes, at 20 right angle with the web part of the rail, the under faces being inclined to the bottom of the rail chamber being driven in the same direction and having no contact with the web part of the rail, the distance between the body portion of the coöperating claws and the cross sectional dimensions of 25 the keys being such that the rail may be

set in a laterally adjustable position whereby different track gages may be obtained at will.

35 6. A fastening device for Vignole rails comprising the combination of a metal supporting member, two lateral opposite claws integral with the said supporting member and having a substantially horizontal projecting or beak portion the inner under side of each beak portion being situated in a plane at right angle with the web part of the rail, but slightly inclined longitudinally 40 toward the rail flange and a body portion 45 and two tapering keys adapted to be forcibly driven between one claw on the said supporting member and one edge of the rail flange, respectively, both keys having their upper faces in slightly inclined planes, at 50 right angle with the web part of the rail, the under faces being inclined to the bottom of the rail chamber being driven in the same direction and having no contact with the web part of the rail, the distance between the beak portions of the coöperating claws being greater than the width of the rail flange, whereby the rail may be inserted 55 into the supporting member or taken off by a vertical movement.

60 In testimony whereof I have signed my name to this specification.

EDMOND FLORIMOND LEVAIRE.
